GIOVANNI BATTISTA CARNOVALI AND ANTONIO CARNOVALI, OF BELLANO, ITALY.

CONTROLLING MECHANISM FOR COCOON-SPINNING MACHINES.

Application filed February 10, 1928, Serial No. 253,457, and in Italy July 22, 1927.

Machines of various types for automatically spinning silk cocoons are known which comprise devices for obtaining strands of constant size. In the earliest forms, the feed 5 of the cocoons is obtained by devices which enter into play when the strand just formed loses in strength on account of the breakage of one of its threads or when one or more cocoons have been completely exhausted. 10 The draw-back of such machines is that the multiple-thread or strand thus obtained shows, in considerable lengths, variations in size at each change-over of cocoons.

Other more modern machines are provided 15 with mechanisms operating when a cocoon escapes from the cluster and becomes engaged in a suitable device, while others are based on the disturbance caused by the escaped cocoon in the hydrodynamic equilibrium 20 of a circulating liquid. In these latter devices, the time lapsing between the instant of breaking away of a cocoon and the hooking-up of a fresh thread is shorter, but not to such an extent as to provide a practically 25 even-sized strand.

The present invention has for its object 30 an improved mechanism for automatically controlling the feed of the cocoon cluster in silk-spinning machines; the special feature 35 of such mechanism or device being its practically-instantaneous operation, which can be obtained with means usually controlled by the tension of the cocoon threads and suitable for actuating devices which secure the proper 40 feeding of the cluster, when the tension of at least one of the threads falls to the point where it is inadequate either through breakage or through exhaustion or else because the thread becomes too thin.

The accompanying drawing illustrates, by 45 way of example and in a somewhat diagrammatic manner, a vertical sectional view of a practical embodiment of the invention; one of the rocker arms being represented in its normal position, and another arm being represented in the position which it assumes when the associated thread breaks or slackens.

The device constituting the invention is 50 mounted to operate in a spinning basin which receives the cocoons; and in the embodiment illustrated, 1 indicates a horizontal disk secured to the upper end of a vertical sleeve 2 which loosely encircles a hollow vertical shaft 3. This shaft 3 is constantly driven at a uniform speed by gearing which is rep-

resented diagrammatically and is generally designated 4; said gearing including a shaft 4' connected to a suitable source of power.

A vertically-movable sleeve 5 is disposed 60 within the relatively-stationary outer sleeve 2 and extends loosely into the upper portion of shaft 3, and it carries adjacent its upper end a ring or spider 6, the arms 6' of which project outward through slots 2' in sleeve 2. 65 The movements of sleeve 5 are controlled by means of a linkage 7 extending through shaft 3 and connected to said sleeve and to a lever 8 which is fulcrumed at one end at 9 and is provided at the other end with a weight 10; 70 the arrangement being such that the downward movement of the lever influenced by weight 10 will pull said sleeve in the same direction. Resetting of said lever to raised position is effected by an eccentric 11. 75

The disk 1 has pivoted to it adjacent its marginal edge a set of rocker arms 12 corresponding in number to the number of cocoons 13 in the cluster, and each of these rocker arms is engaged at its upper end with the 80 thread 14 from the associated cocoon; the several threads passing to the central aperture 15 of a rose 16, and thence, via the twisting or condensing device 17, to a feeding device or mechanism (not shown) which may 85 be of any usual or suitable character. The aperture 15 is disposed in line with the axes of disk 1 and of the parts 2, 3 and 5; and the tension which is normally imposed on the threads by the device 17 is such that the upper ends of the rocker arms 12 are swung 90 inward. The arms are so shaped that, when free, they tend to assume the position shown, in the case of the right-hand arm, in dotted lines; whereas, when subjected to the normal 95 tension of the threads, they are rocked into the position represented in full lines for the right-hand arm.

As has already been stated, the hollow shaft 3 is subjected to a constant or continuous rotation at uniform speed by means of the gearing 4. The outer sleeve 2 which carries the disk 1 is spaced from the shaft 3, as is also the inner sleeve 5 to which the spider 6 is attached, so that under ordinary conditions the 100 two sleeves and the disk and spider are stationary. Now, the arms 12 rock automatically, due to the offset shape and superior weight of their lower portions, when the tension of the cocoon threads falls below a pre-determined degree from any cause, and in 110 particular when the thread slackens or

breaks; one feature of our invention residing in the employment of this return movement of the rocker arms to couple their carrier disk 1 to the rotating shaft 3 to be driven thereby. 5 Accordingly, we provide said shaft with a coupling element 18, here shown as a crown wheel fixed to the shaft, the teeth 19 of which are engaged by the lower end 20 of a rocker arm when the corresponding thread loosens 10 or breaks. When this occurs, the outer sleeve 2 and its disk 1 will be coupled to the shaft 3 to rotate therewith, and the inner sleeve 5 will likewise be rotated, since the arms 6' of its spider project through the slots 2' in 15 sleeve 2.

The rotation of the parts 2, 1 and 12 is utilized to effect the automatic tripping of the lever 8, which latter is normally retained in raised position by a catch 21 in the form 20 of a bell-crank lever that is subjected to the action of a retractile coil spring 22 attached to a stationary part of the apparatus. The upper or horizontal arm of the bell-crank is operatively connected to a ring 23 that 25 loosely encircles the crown wheel 18; and this ring 23 is provided on its upper edge with a single projecting lug or member 24 that is disposed in the path of the end 20 of the rocker arm coupled to the crown wheel. 30 Hence, as the rotation of the crown wheel proceeds, the aforesaid arm end 20 will strike against this projection and thereby impart a rotary shifting movement to ring 23 which 35 will serve to rock the bell-crank. The latter has a hook 25 at the lower end of its vertical arm across which the lever 8 extends and is supported, and this hook is withdrawn by the 40 rocking movement of the bell-crank just mentioned, so that lever 8 then falls instantly, due to the provision of weight 10, carrying down with it a lever 26 which likewise underlies lever 8 and which is connected to control the 45 device (not shown) that effects the substitution of a fresh cocoon for the exhausted or 50 detached cocoon. The rotary movement of ring 23 is of comparatively slight extent, and that of the carrier 1 at most will not exceed one revolution before the rocker arm 12 which 55 is released from its thread strikes against the projection 24. The speed of rotation of the crown wheel is so calculated that the substitution of the fresh cocoon will take place 60 practically instantly.

In addition to operating the controlling 55 lever 26, the downward movement of lever 8 is utilized to effect the disengagement of the rocker arm (or arms, if more than one be engaged) from the crown wheel 18, as well 60 as the arm engaged with projection 24. This 65 action takes place through the agency of the linkage 7 which pulls the inner sleeve 5 downward, whereupon the spider 6 will be caused to strike against the engaged rocker arm with its beveled outer edge 6' and cam the same 70 outward as the spider descends. The eccen-

tric 11 may then be actuated to lift lever 8 into its normal position and reengage it with the bell-crank hook 25 ready for another operation.

In order to prevent a defective or faulty 70 action of the structure in case the twisted strand breaks after passing beyond the condensing or twisting device 17, an accessory device is provided to block the movement of the rocker arms 12 into engagement with 75 wheel 18. Such device is here shown as comprising a second ring 27 which surrounds the ring 23 and has an appreciably greater diameter, so that a substantial space separates the two rings. The ring 27 normally rests upon 80 the inner end of a centrally-pivoted lever 28, the outer end of which is articulated to the lower end of a vertical rod 29 provided at its top with a hook 30; and the latter is normally engaged with a hook 31 carried by a counter-weighted roller 32 over which the twisted strand 33 passes after leaving the tensioning or condensing device 17. Hence, if the strand 33 should break, the counterweighted roller 32 would turn in a direction to disengage its 85 hook 31 from the hook 30 on rod 29, whereupon the latter would fall and, in so doing, rock the lever 28 in a manner to lift up the blocking ring 27 far enough to project between the lower ends of the rocker arms and 90 the teeth 19 of the crown wheel 18.

It is to be understood that the reeling or other mechanism or device to which the twisted strand 33 passes from the roller 32, 100 may be of any suitable or preferred character and, in any event, forms no part whatever of the invention itself. The same is equally true of the mechanism or device for substituting a fresh cocoon for an exhausted or 105 escaped cocoon, and for that reason no illustration of these devices has been given, as it is entirely immaterial what form they may take in practice.

We claim as our invention:

1. In a controlling mechanism for cocoon spinning machines, a set of coupling members each normally held against action by a tensioned thread from a cocoon, but automatically executing its active movement when such tension falls below a predetermined degree; a normally-stationary carrier for said coupling members; a device to control the cocoon feed; a constantly-rotating element adapted to be coupled with said carrier to rotate the same, by the active movement of a coupling member; and means actuated by the rotation of the carrier for effecting operation of the feed-controlling device.

2. In a controlling mechanism for cocoon spinning machines, a set of rockers each normally held against action by a tensioned thread from a cocoon, but automatically executing its active movement when such tension falls below a predetermined degree; a normally-stationary carrier for said rockers;

5 a device to control the cocoon feed; a constantly-rotating element; means on said rotating element for engagement by a rocker during its active movement to couple the rotating element with said carrier to rotate the same; and means actuated by the rotation of the carrier for effecting operation of the feed-controlling device.

10 3. In a controlling mechanism for cocoon spinning machines, a set of rockers each normally held against action by a tensioned thread from a cocoon, but automatically executing its active movement when such tension falls below a predetermined degree; a 15 normally-stationary carrier for said rockers; a device to control the cocoon feed; a constantly-rotating shaft; a crown wheel fixed to said shaft and having teeth for engagement by a rocker during its active movement to 20 couple the carrier to said crown wheel for rotation therewith; and means actuated by the rotation of the carrier for effecting operation of the feed-controlling device.

25 4. A controlling mechanism according to claim 3, in which the teeth of the crown wheel project laterally outward, and the rockers are mounted in vertical position and are adapted to engage said teeth at their lower ends.

30 5. A controlling mechanism according to claim 3, in which the teeth of the crown wheel project laterally outward, and the rockers have offset lower portions which cause them to swing inward automatically into engagement with said teeth.

35 6. In a controlling mechanism for cocoon spinning machines, a set of coupling members each normally held against action by a tensioned thread from a cocoon, but automatically executing its active movement when such tension falls below a predetermined degree; a normally-stationary carrier for said coupling members; a device to control the cocoon feed; a constantly-rotating element 40 adapted to be engaged by a coupling member during its active movement and thereby coupled with said carrier to rotate the same; means actuated by the rotation of the carrier for effecting operation of the feed-controlling device; and means for automatically disconnecting said coupling member from said rotating element after the carrier has completed a rotation of predetermined extent.

45 7. In a controlling mechanism for cocoon spinning machines, a set of coupling members each normally held against action by a tensioned thread from a cocoon, but automatically executing its active movement when such tension falls below a predetermined degree; a normally-stationary carrier for said coupling members; a device to control the cocoon feed; a constantly-rotating element adapted to be engaged by a coupling member during its active movement and

thereby coupled with said carrier to rotate the same; means actuated by the rotation of the carrier for effecting operation of the feed-controlling device; a member for releasing the coupling member engaged with the rotating element; and means for automatically operating the releasing member after the carrier has completed a rotation of predetermined extent.

8. In a controlling mechanism for cocoon spinning machines, a set of coupling members each normally held against action by a tensioned thread from a cocoon, but automatically executing its active movement when such tension falls below a predetermined degree; a normally-stationary carrier for said coupling members; a device to control the cocoon feed; a constantly-rotating element adapted to be engaged by a coupling member during its active movement and thereby coupled with said carrier to rotate the same; means actuated by the rotation of the carrier for effecting operation of the feed-controlling device; a vertically-movable spider disposed between the coupling members for releasing the member engaged with the rotating element on downward movement of the spider; and means for automatically operating said spider after the carrier has completed a rotation of predetermined extent.

9. In a controlling mechanism for cocoon spinning machines, a set of coupling members each normally held against action by a tensioned thread from a cocoon, but automatically executing its active movement when such tension falls below a predetermined degree; a normally-stationary carrier for said coupling members; a normally-inactive trip lever operable to control the cocoon feed; a constantly-rotating element adapted to be engaged by a coupling member during its active movement and thereby coupled with said carrier to rotate the same; and means for automatically tripping said lever to enable its operation consequent upon the rotation of the carrier.

10. A controlling mechanism according to claim 9, in which the automatic tripping means comprise a catch normally engaged with the trip lever, and a movable member actuated by the engaged coupling member for disengaging said catch.

11. A controlling mechanism according to claim 9, in which the automatic tripping means comprise a catch normally engaged with the trip lever, and a shiftable ring loosely encircling the rotating element and actuated by the coupling member engaged with said element for disengaging said catch.

12. In a controlling mechanism for cocoon spinning machines, a set of coupling members each normally held against action by a tensioned thread from a cocoon, but automatically executing its active movement

when such tension falls below a predetermined degree; a normally stationary carrier for said coupling members; a normally-inactive trip lever operable to control the cocoon feed; a constantly-rotating element adapted to be engaged by a coupling member during its active movement and thereby coupled with said carrier to rotate the same; means for automatically tripping said lever consequent upon the rotation of the carrier; and means operated automatically consequent upon the tripping of the lever for releasing the engaged coupling member from the rotating element.

15 13. In a controlling mechanism for cocoon spinning machines, a set of coupling members each normally held against action by a tensioned thread from a cocoon, but automatically executing its active movement when such tension falls below a predetermined degree; a normally-stationary carrier for said coupling members; a normally-inactive trip lever operable to control the cocoon feed; a constantly-rotating element adapted to be engaged by a coupling member during its active movement and thereby coupled with said carrier to rotate the same; means for automatically tripping said lever consequent upon the rotation of the carrier; a member for releasing the engaged coupling member from the rotating element; and a connection between the trip lever and releasing member for operating the latter when the former is tripped.

35 14. In a controlling mechanism for cocoon spinning machines, a lever operable to con-

trol the cocoon feed; means normally holding the lever against operation; a plurality of coupling members each normally held against action by a tensioned thread from a 40 cocoon, but automatically executing its active movement when such tension falls below a predetermined degree; a normally-stationary carrier for said coupling members; a constantly-rotating element adapted to be 45 coupled with said carrier to rotate the same by the active movement of a coupling member; means operable by the rotation of the carrier for releasing the control lever; means for twisting together the individual threads to 50 form a tensioned, multi-thread strand; and means operated automatically when the tension of the strand falls below a predetermined degree for blocking the coupling movement of the coupling members.

55 15. A controlling mechanism according to claim 14, in which the blocking means comprises a shiftable ring and means for moving it into position to prevent effective movement of the movable members.

60 16. A controlling mechanism according to claim 14, in which the movable members consists of a series of pivoted rockers and a support therefor; and in which the blocking means comprises a vertically-movable ring and means for moving it into position to prevent effective movement of the rockers.

In testimony whereof we affix our signatures.
